UNITED STATES PATENT OFFICE.

WILLIAM HUNTINGTON RUSSELL, OF NEW HAVEN, CONNECTICUT.

COIN-CHANGING MACHINE.

Application filed January 11, 1923. Serial No. 612,081.

The invention relates to improvements in a coin changing machine, which may be regulated to give an equal value in coins of any desired denominations in exchange for any 5 coin inserted into the machine through its correct slot. Coins inserted to be changed may themselves be given in change for coins of higher denominations.

With these and other advantages which 10 will be set forth, the machine is easily constructed, simple in operation, cannot be cheated and is readily adapted to meet varying requirements in regard to the amount and denominations of change to be given or 15 deducted for any coin inserted in its correct slot, as will be fully set forth.

In the drawings,

Fig. 1 is a longitudinal section view of the machine;

Fig. 2 is a vertical section through the machine;

Fig. 3 is a plan view of the coin slots;

Fig. 4 is a plan view of the sliding plates with cushioned slots;

Fig. 5 is a plan view of the coin magazines and means of obtaining change;

Fig. 6 is a variation of Fig. 4 showing the coin plates separated;

Fig. 7 is a variation of Fig. 1, showing a 30 machine designed to operate with fewer denominations of coins, and in which several coin magazines, including the extra nickel magazine, have been omitted.

In the preferred form of the invention, 1 35 represents the general body of the machine, which may be of any desired shape or size, having doors 2 on opposite sides opening on hinges 3. There are separate coin slots 4 through the top of the machine, as shown in 40 Fig. 3, for inserting each size coin which is to be changed. Each of said slots is large enough for the coin for which it is made, to go through, but not large enough for coins of greater size to pass into the machine. 45 Said coin insertion slots are arranged in order, according to the denomination of the coins to be changed, beginning with the largest, the various denominations of the said coin insertion slots, alternating in two 50 parallel rows. Under each of the said insertion coin slots there is a coin guide 5, shown in Fig. 1, which will direct any coin admitted through any of the insertion slots to a second coin slot, 6 on a plate 8; each 55 of the said second coin slots is slightly

wider at its top than at its bottom. A spring or cushion regulates the size of the coin which can pass through a slot. Each of the said second coin slots 6 is on a separate plate 8. Each of said plates 8 is disposed end to end between two grooved supports 9, in which they are slidable in the same direction and in the same plane. Said plates are arranged in order from the plate having the cushion slot for the highest denomination coin to the plate having the lowest denomination coin in its cushion slot. A coiled spring 10 acting on the lowest denomination coin carrying plate will bring all the said cushion slots back to a position 60 directly under a corresponding denomination coin insertion slot, when the force which has moved any or all of the said plates out of said position has been removed. The highest denomination coin carrying 65 plate will come to rest in that position against its stop 11, and each of the said plates will then hold the next plate to it in the same relative position, with its coin slot directly under the corresponding insertion slot. A coin pusher 12 slides between two cuts 13 in the cover of the machine on 70 its supports 14 and having its handle 15 extending above the machine, and its base 16 resting on the grooved supports 9 on 75 which the said base slides. One end of a coiled spring 17 is attached to the said pusher at 16 and the other end attached to the machine at 19, said spring going over a 80 roller 36. Near one end of each of the said 85 guides 5 is a flat piece of metal 20, fastened under the cover of the machine in such a way that a coin carried in a cushion slot 6 and coming into contact with the said piece of metal 20 will swing it away from the 90 said guide 5, but the said guide 5 will keep the said piece of metal from swinging in the other direction when a coin comes 95 against it from the opposite side.

There is one coin pressing device 21 for 100 each cushion coin slot 6, each of said devices 21 being attached to the cover of the machine on its under side in such a way that any coin carried in a cushion slot a sufficient distance by the handle 12 will come 105 in contact with a presser 21 and the said cushion or spring 7 will then allow the said coin to be pushed through its slot 6.

Directly under each of the two grooved supports 9 there is a row of coin magazines 110

22 attached to supporting rods 23 as shown in Figs. 1 and 2. One row of said magazines comprises coins of fifty, nickel and dime denominations in the order named, the 5 said nickel magazine having its upper section 37 extending out of the machine for inserting coins in, and being different from the others as will be stated below and referred to as the extra nickel magazine. The 10 other row of magazines comprise one magazine for twenty-five cent coins, and one magazine for coins of five cent denomination as shown in Fig. 5. At one end of each of said rows, which are parallel, is another row of 15 five magazines 22, Fig. 4, of penny denominations having a cover 40 as shown in Fig. 3. Each of said magazines 22 except those for the pennies, the highest denomination coin—the dollar—and the extra nickel, has one 20 end of a coin chute 24 fastened to it. The other end of said coin chute is adjacent to one end of each cushion slot for coins of the same denomination as the magazine to which the other end of said chute leads. Said 25 chutes 24 are so situated that all coins are forced through the said cushion slots by the pressers 21, and will slide down the said chutes 24 to their respective coin magazines. When any of the said magazines 22 are full 30 of coins the overflow will be carried down said chutes 24 and will slide over the top of the coins in the said magazines 22, and will then fall through the opening 46, and into one of the drawers 31, 32, located on each 35 side of the machine. Each of said drawers is opened by means of its handle 33. As the dollar coin is not given in change it is carried down the chute 44 by means of gravity through the opening 46 into 31 having a 40 lock 39 and any other coin may likewise go directly into a coin drawer instead of its magazine by adjusting its coin chute accordingly. All coins falling through coin slots before they have been moved a sufficient 45 distance to come in contact with a presser will, on falling through their respective slots, fall onto a bell 25 situated directly under each of said coin slots, and then slide off the bell and fall through the opening between the 50 plates 28 shown in Fig. 5, and then slide down the incline 26 and out of the machine at 27. Sliding on its support just above the bottom of each coin magazine and of the approximate thickness equal to the coin in its 55 respective magazine is a plate 28 having a circular outline aperture 29 therein, corresponding to the size of the bore of the magazine under which the said plate is located. Said plates are mounted to slide just over 60 the supporting partition 34 of their respective coin magazines, and produce one coin from its magazine. Each plate 8 has a cushioned slot for coins of different denominations, the slot in each plate being of different 65 size, and each has a separate rod 30 riveted to it, the other end of the said rod 30 being releasably attached to the plate 28 which slides under a coin magazine of one denomination lower. The said rods 30 extend and operate in an open space between the two 70 parallel rows of coin magazines, and coins too small for any slot drop through said open space onto the incline plane 26, and then slide out of the machine through the exit 27. The two plates 8 and 28 which are fastened to the ends of each rod 30, must move together unless the plate 28, which is under a coin magazine is disconnected from its rod, in which case said plate 28 will not be moved by the said rod 30, and one coin of 80 the denomination ordinarily obtained when said plate is moved, will be deducted in giving change. The plate having the dollar cushion slot is connected to the plate under the fifty cent magazine, likewise the plate 85 with the fifty-cent cushioned slot is connected to the plate under the twenty-five cent magazine. The plate carrying the twenty-five cent coin is connected to the plate under the dime magazine. This plate under the 90 dime magazine is long enough to extend back under the said extra nickel magazine and is so constructed that when moved a sufficient distance, both a dime and a nickel will be obtained from their respective magazines. 95 The plate carrying the dime cushioned slot is likewise fastened to and controls the plate under the nickel magazine, and the plate carrying the nickel cushioned slot is connected to a plate which slides under all the penny 100 magazines and is so constructed that it will obtain one penny from each magazine. Unless one or more of said change obtaining plates 28 is disconnected from a rod 30 as stated above, coins inserted will produce 105 the following change when the machine is operated. A nickel inserted through its correct slot will produce five pennies. A dime inserted will produce a nickel and five pennies; a quarter inserted will produce the extra nickel, a dime, the ordinary nickel and five pennies. A fifty-cent piece will produce in change a quarter, the extra nickel, a dime, the ordinary nickel and five pennies. And a dollar coin inserted will produce fifty-cents, 110 a quarter, the extra nickel, a dime, the ordinary nickel and five pennies. To keep coins out of any insertion coin slot, a set screw 35^A is placed through the guide 5 under the said insertion slot, as shown in Fig. 1. One end of a pivoted plate 20 is pivoted to the casing so that a coin made to actuate the machine by means of pushing the handle against the coin, will lift the pivoted plate a sufficient distance to allow the coin to pass, 115 but after the coin has once passed the pivoted plate will not allow it to return as the guide 5 will keep the pivoted plate from lifting.

To operate the machine, a coin to be 120 125 130

changed is dropped into the correct insertion slot through the cover of the machine; said coin will then fall through said slot and be directed by the said guide 5 to its 5 cushion coin slot 6 in which it rests. The handle 12 is then moved, its base 16 passing each successive plate not having a coin in its cushioned slot until it comes in contact with a coin in a cushioned slot. The 10 plate having the said coin in its cushioned slot, and all the plates with cushioned slots for coins of smaller denomination, will be moved in the same direction, but the plates having cushioned slots for larger denomination 15 coins will not be moved. Each of the said plates under the coin magazines which are connected by means of the rods 30 to any of the plates moved by base 16 of the handle 15 coming in contact with the said 20 coin in a cushioned slot will themselves be moved a sufficient distance for each to produce one coin from its respective magazine. The said coin will be carried so that it will raise the pivoted plate 20 to a sufficient 25 height to allow the coin to pass under it, and the coin will then eventually come in contact with the depresser 21 at a point where it is directly over its coin chute 24 and said coin will then be forced through 30 its cushioned slot by its said depresser 21 and fall into its chute 24 and be carried to its respective coin magazine, where the said coin will eventually be given as part change for a coin of higher denomination. 35 Any coin produced as change from its magazine will be carried down the inclined plane 26 and out of the exit 27. When the said coin has been removed from its cushioned slot the spring 10 will bring the various 40 moved parts of the machine back to their original position, with the exception of the handle, which on being released will be brought back to its original position by the spring 17, and the machine will be ready 45 for operation again. By disconnecting any number of plates 28 under the coin magazines from the rods 30 to which each is connected by means of a screw a regulated amount of change may be deducted each 50 time the machine is operated. Assuming it is desired to deduct six cents from any coin inserted to be changed, it is only necessary to empty one of the penny magazines and the nickel magazine of their respective coins. 55 In this case the spring or cushion under the slot in the nickel carrying plate would be adjusted so that a nickel would fall freely through the slot without operating the machine, as the value to be deducted 60 in this case is more than the value of a nickel. The nickel would slide down the inclined plane 26 and to the exit 27. Any amount of change may be deducted in like manner or the same effect may be accomplished by emptying all the coins from

magazines corresponding to the change desired to be deducted.

Only coins of correct size for each slot will have any effect on the machine as the others will either not be admitted or will 70 fall through and be returned to its owner.

Fig. 6 shows how shorter cushioned coin slot plates may be substituted for the longer ones, each of said plates having a separate spring 42 which normally holds it against a 75 set screw 41 inserted through one of the groove supports. This is accomplished by having one end of the spring 42 fastened to the set screw 41 and the other end fastened to the sliding plate at 43. In this 80 way the said plates are separated, and each may be moved in its grooved supports without moving any other cushioned slot plates, and each of said plates can only move the 85 change obtaining plate 28 to which it is connected. By inserting a shorter plate or bumper between each of the said cushioned slot plates and removing the set screws in the grooved supports, and adjusting one or more of the springs, the said plates will 90 operate as in Fig. 4.

In Fig. 7 all the coin magazines are in a single row, and several have been eliminated including the extra nickel and four 95 of the penny magazines. The plate under the penny magazine is made thick enough to obtain five pennies each time it is moved. A chute 45 may direct the largest denomination coin to a coin drawer located on either side of the machine. When this principle 100 of obtaining more than one coin from each magazine is applied with the shorter plates shown in Fig. 6, it is possible to obtain the highest denomination of change for each coin inserted in the machine. The number 105 of times the machine is used may be shown by having the piece of metal 34^a operate a register as shown in Fig. 7.

The various springs on the machine may 110 operate in any way, and this includes the cushions on the coin slots which may consist of any material and located in any position in which they will stop the largest size of coins admitted into their respective slots from falling through said slots of their own 115 weight. I do not limit myself to any special number, height, denominations or arrangements of the coin magazines. Neither do I limit myself to any special method of obtaining change from the said magazines. 120

This is what I claim:

1. A coin changing machine comprising a frame, a plurality of coin carrying plates arranged to receive coins of different values means to actuate said plates through a coin 125 and means to eject said coin from said plate, said plates being horizontally disposed end to end and movable in said frame against a spring, coin magazines attached to said frame and means selectively connected to 130

the coin carrying plates for ejecting coins of selected denominations from said coin magazines.

2. A coin changing machine comprising a casing having coin slots of different sizes, a frame attached to said casing, a plurality of coin carrying plates, slideable in said casing, arranged to receive coins of different values, means to actuate said plates through a coin, coin magazines attached to said frame and means to eject said coin from its carrying plate, said plates being horizontally disposed end to end, movable in the same plane against a spring and means selectively connected to the coin carrying plates for ejecting coins of selective denominations from said coin magazines.

3. A coin changing machine comprising a frame attached to a casing, a plurality of coin carrying plates, horizontally disposed end to end, movable in said frame against a spring, coin magazines attached to said frame, each plate having a different size coin slot therein and each coin slot having a spring in one end, means to actuate said plates through a coin against a spring and means to eject said coins through said slot in said plate, and means selectively connected to the coin carrying plates for ejecting coins of selective denominations from said coin magazines.

4. A coin changing machine comprising a frame, coin magazines attached to said frame, a plurality of coin carrying plates having slots arranged to receive coins of different sizes, a movable handle to actuate said plates through a coin and means to eject said coin from said plate, said plates being horizontally disposed end to end and movable in said frame against a spring and means selectively connected to the coin carrying plates for ejecting coins of selective denominations from said coin magazines.

5. A coin changing machine comprising a frame, a plurality of coin slotted plates, each plate arranged to receive a coin of a different size in its slot, releasably held in its slot by means of a spring in one end of said slot, a device for pressing a coin of a regulated size through its slot, coin magazines attached to said frame, means to actuate one or more of said plates through a coin in one direction, a pivoted plate for keeping any plate having a coin in its slot and moved in one direction from being actuated by a spring in the opposite direction, and means selectively con-

nected to the coin carrying plates for ejecting coins of selective denominations from said coin magazines.

6. A coin changing machine comprising a frame, coin magazines attached to said frame, a plurality of coin carrying plates, each of said plates having a different size coin slot and a spring in one end of the slot, a movable coin pusher arranged to actuate any plate through a coin in its slot, means to eject a coin through a slot in a sliding plate, means to carry any coin so ejected into a coin magazine, means selectively connected to the coin carrying plates for ejecting coins of selective denominations from said coin magazines attached to said frame and a coin slide for bringing said ejected coins out of said machine.

7. A coin changing machine comprising a frame, coin magazines attached to said frame, a plurality of coin carrying plates, each of said plates having a different size coin slot and a spring in one end of the slot, a movable coin pusher arranged to actuate any plate by coming in contact with a coin in one of said slots; means to guide said coin through a coin insertion slot into one of said slots on a plate; means to eject a coin through a slot on said plate and means to carry a coin so ejected into a coin drawer; rods selectively connecting the coin carrying plates to coin ejectors located near the base of said coin magazines attached to said frame and means for returning coins so ejected to the person operating the machine.

8. A coin changing machine comprising a casing, having different size coin slots through it, a frame fastened in said casing, coin magazines attached to said frame, a plurality of plates each having a different sized coin slot through it and each plate having a spring attached so that one end of said spring will extend a short distance within one end of said coin slot; means to guide coins to each of said coin slots in said plates; means to actuate said plates through a coin held in said coin slot, means to release said coins from said coin slots, coin ejectors connected to said plates by means of rods for ejecting the bottom coin in a coin magazine attached to said frame, and means for returning said ejected coins to one end of said machine.

In testimony whereof I affix my signature.

WILLIAM HUNTINGTON RUSSELL.
